UNITED STATES PATENT OFFICE.

HENRY BERRY, OF SHELTON, CONNECTICUT, ASSIGNOR TO THE DERBY SILVER COMPANY, OF SAME PLACE.

DESIGN FOR A HANDLE FOR BRUSHES, &c.

SPECIFICATION forming part of Design No. 18,976, dated March 26, 1889.

Application filed February 16, 1889. Serial No. 300,171. Term of patent 7 years.

To all whom it may concern:

Be it known that I, HENRY BERRY, a citizen of the United States, residing at Shelton, in the county of Fairfield and State of Connecticut, 5 have invented and produced a certain new and original Design for a Handle for Brushes and Similar Articles, of which the following is a specification, reference being had to the accompanying drawing, forming a part thereof, 10 and which shows a plan view of a handle shaped and ornamented in accordance with my design.

The leading features of my design consist in the peculiar shape or outline of the handle, 15 the fluted figures which appear as extending vertically upon the body of the handle, and the foliate cap which finishes the extremity of said handle. At *a* the handle is swelled outwardly, and thence it tapers downwardly in 20 a slightly-curved outline to the point *b*, and is turned somewhat outward with respect to the body of the handle. Upon the handle appear

the fluted figures *c*, which cover the whole upper portion of the handle and which follow its outline downward, diminishing in size as 25 they approach the end thereof. The extremity of the handle has upon it the representation of a foliate figure, *d*, appearing as enfolding said extremity.

I claim—

The design for handles for brushes and similar articles, as herein shown and described, the same having the enlarged upper portion, and tapering and curving thence downward to its extremity, and having also the fluted 35 figures covering the body of the handle and extending lengthwise thereof, and the foliate cap upon the end of said handle, as specified.

In testimony whereof I affix my signature in presence of two witnesses.

HENRY BERRY.
